UNITED STATES PATENT OFFICE.

CHARLES L. VAN INWAGEN, JR., OF RUTHERFORD, NEW JERSEY, ASSIGNOR TO WESTERN ELECTRIC COMPANY, INCORPORATED, OF NEW YORK, N. Y., A CORPORATION OF NEW YORK.

CONVEYER.

Application filed December 8, 1920. Serial No. 429,255.

To all whom it may concern:

Be it known that I, CHARLES L. VAN INWAGEN, Jr., a citizen of the United States, residing at Rutherford, in the county of Bergen, State of New Jersey, have invented certain new and useful Improvements in Conveyers, of which the following is a full, clear, concise, and exact description.

This invention relates to conveyers and especially to a mechanical ticket distributing system such as is employed in telephone exchanges for sending information or instructions from one operator to another.

An object of this invention is to move a hoist arm from a trackway remote from a ticket depositing position and to return said hoist arm to a position in proximity to said trackway.

Another object of this invention is to provide motive means for moving a hoist arm between receiving and discharging positions.

This conveyer or ticket hoist comprises a casing attached to the main guides. Located in the casing is a spring and two gears controlled thereby. Attached to one of the gear wheels is a U-shaped guide which serves as a hoist arm. The hoist arm is normally held in line with the guides but a flexible member is attached for drawing it down. The lowering of the hoist arm energizes a spring which raises the hoist arm to its normal position when the flexible member is released.

The invention will be more clearly understood by reference to the following detailed specifications and accompanying drawings.

Fig. 1 is a perspective view of a ticket distributing system with the ticket hoist in position.

Fig. 2 is a side view of the device with a part of the casing broken away to show the spring controlled gears.

Fig. 3 is a cross section along the line 3—3 of Fig. 2.

A main guide 1 has a spur guide 2 joining it at 12. Casing 3 is attached to the guides by any means such as screws 13. Located in the casing 3 is a spring 4 one end of which is attached to the casing at 5 and the other

end is attached to a gear wheel 6 which is 50 rotatably mounted on a shaft 7. A gear wheel 8 meshes with gear wheel 6 and is rigidly attached to a shaft 9 which is rotatably mounted in the casing 3. A bracket 10 is also mounted on the shaft 9 and is 55 rigidly attached to the same by means of a screw 16 which engages with the slide-way of lever 15 which is fixed to shaft 9. The bracket 10 carries a hoist arm 11 at one end of which is a ticket holding compartment 14. A spring 17 is fastened at one end to the casing 3 by means of the screws 18 and provided at the other end with a roller 30 that normally engages the projection 31 on the side of the bracket 10; the roller being 60 held against this projection by the tension spring 17 so as to lock the hoist arm 11 in normal position. An adjustable screw 32 is provided on the bracket 10 to adjust the alignment of the hoist arm in relation to the 65 spur guide 2. A flexible member 19, which passes over pulleys 20 in order that it may be brought to a suitable position, serves as a means for exerting a force on the hoist arm to lower the same. 21 is a trolley which 70 moves the tickets along the guides. A receptacle 22 provides means for mounting the main ticket guides independently of the spur guides 2. Screws or bolts 23 are provided 75 for retaining the receptacle 22 on the supporting member 24.

In Fig. 1 an outlet guide 25 is disclosed not as part of the invention, but to make the drawing more complete and to show the position of the hoist arm 11 relative to such outlets which are mounted at each operator's position. A ticket 27 is shown in the act of being delivered to the operator through the guide 25. A clamping device 26 for retaining the ticket 27 within view of the operator until she is prepared to remove it, is located at the free end of guide 25. An aperture 28 in the outlet guide 25 furnishes means for clearing out the guides should a ticket become lodged therein. The light lines in Fig. 2 show a section of the hoist arm in its operated position.

The operation of the device is as follows:

Starting with the hoist arm 11 in its normal position where it is locked by spring 17, a force is exerted on the flexible member 19. This force overcomes the locking power of the spring 17 and causes the hoist arm 11 to descend. The downward movement of the hoist arm 11 energizes the spring 4 through gears 8 and 6. A ticket is then inserted in the ticket compartment 14 and the flexible member 19 is released. The spring member then raises the arm 11 to its normal position in which it is locked by spring 17. The trolley 21 carries the ticket along spur guide 2 into the main guide 1.

15 What is claimed is:

1. In a ticket distributing system including guides and spur guides, a ticket hoist comprising a pivoted hoist arm, means for holding said hoist arm in and raising it to its normal position, means for lowering said hoist arm and means for energizing said raising means by lowering said hoist arm.

2. In a ticket distributing system including guides and spur guides, a ticket hoist attached to said guides, said hoist comprising a pivoted hoist arm, and spring controlled gears for operating said hoist arm.

3. In a ticket distributing system including guides and spur guides, a ticket hoist comprising a pivoted hoist arm, a spring for retaining said hoist arm in and raising it to its normal position, a flexible member for lowering said hoist arm and gears for energizing said spring operated by lowering said hoist arm.

4. In a ticket distributing system including guides and spur guides, a ticket hoist comprising a casing attached to said guides, a spring and spring controlled gears located in said casing and a hoist arm attached to one of said gears and held in and raised to its normal position by said spring.

5. In a ticket distributing system including guides and spur guides, a ticket hoist comprising a casing attached to said guides, a spring and spring operated gears located in said casing, a hoist arm fixed to one of said gears and held in and raised to its normal position by said spring and a flexible member attached to said hoist arm for lowering the same.

6. In a ticket distributing system including guides and spur guides, a ticket hoist comprising a casing attached to said guides, a spring and spring operated gears located in said casing, a hoist arm fixed to one of said gears and held in and raised to its normal position by said spring, a second spring for locking said hoist arm in its normal position and a flexible member by which said hoist arm may be lowered.

7. In a ticket distributing system including guides and spur guides, a ticket hoist comprising a casing attached to said guides, a spring and spring operated gears located

in said casing, a hoist arm fixed to one of said gears and held in and raised to its normal position by said spring, a ticket holding compartment carried by said hoist arm, a second spring for locking said hoist arm in its normal position, and a flexible member by which said hoist arm may be lowered.

8. In a ticket distributing system comprising guides and spur guides, a ticket hoist comprising a casing attached to said guides, a spring and spring controlled gears located in said casing, a hoist arm fixed to one of said gears and retained in and raised to its normal position by said spring and a spring adjusting lever fixed to said gear and adjustably attached to said hoist arm.

9. In combination with a ticket distributing system including guides and spur guides, a ticket hoist comprising a casing attached to said guides, a spring located in said casing and having one end attached thereto, a gear wheel pivoted in said casing and having the other end of said spring attached thereto, a second gear wheel pivoted in said casing and meshing with said first gear and a hoist arm attached to said second gear and retained in and raised to its normal position by said spring.

10. In combination with a ticket distributing system including guides and spur guides, a ticket hoist comprising a casing attached to said guides, a spring located in said casing and having one end attached thereto, a gear wheel pivoted in said casing and having the other end of said spring attached thereto, a second gear wheel pivoted in said casing and meshing with said first gear, a hoist arm attached to said second gear and retained in and raised to its normal position by said spring, a spring adjusting lever attached to said second gear, a second spring for locking said hoist arm in its normal position and a ticket holding compartment carried by said hoist arm.

11. In a ticket distributing system, a ticket guide, a hoist arm rotatably mounted at one end adjacent the guide, means at some distance from the mounting end of said hoist arm for moving it to receive tickets and spring controlled means at the mounting end of the hoist arm controlled by said first means for storing energy during such movement to restore said hoist arm to normal.

12. In a ticket distributing system, a hoist arm arranged to receive tickets and rotatably mounted at one end, means located at some distance from the mounting point of said hoist arm for moving it from its normal position, and spring controlled means at the mounting point of said hoist arm controlled by said first means for storing energy during such movement to return the hoist arm to its normal position.

13. In a ticket distributing system, a main

ticket guide, a spur guide, a hoist arm having a ticket receiving compartment, means for retaining the hoist arm in its normal position, means for moving the hoist arm to deposit tickets in said compartment, means for storing energy to return said hoist arm to normal position when the tickets are de-

posited, and means for moving the tickets from the compartment via the spur guide to the main guide. 10

In witness whereof, I hereunto subscribe my name this 2nd day of December A. D., 1920.

CHARLES L. VAN INWAGEN, JR.
